UNITED STATES PATENT OFFICE.

CHARLES REINISCH AND LOUIS OCHSE, OF NEWARK, NEW JERSEY.

BAG-CATCH.

SPECIFICATION forming part of Letters Patent No. 360,113, dated March 29, 1887.

Application filed January 17, 1887. Serial No. 224,553. (No model.)

To all whom it may concern:

Be it known that we, CHARLES REINISCH and LOUIS OCHSE, citizens of the United States, residing at Newark, in the county of Essex and 5 State of New Jersey, have invented certain new and useful Improvements in Bag-Catches; and we do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

15 In the accompanying sheet of drawings, Figure 1 is a plan or top view of the closed frame-sections of a bag to which the improved catches are attached. Figs. 2 and 3 are side elevations of portions of the frame-sections and the 20 catches attached thereto in a locked and unlocked position, respectively. Fig. 4 is a transverse section of Fig. 2 through x. Fig. 5 is a similar view taken through x' on Fig. 3. Figs. 6 and 7 are sectional views taken through 25 y and y', Figs. 4 and 5, respectively.

Similar letters of reference indicate corresponding parts in each of the views.

The catch illustrated in the above-described views consists of a spring-actuated catching-bar, a, having a rounded head, a', a shoulder, a'', a barbed or conical end, a'', above which is an annular recess, a'', and a spring detaining or catching plate, b, having a projecting portion, b', in which is an opening, b'', adapted to 30 receive the barbed end of the catching-bar. Said catching-bar and detaining-plate are provided with or arranged in suitable casings—that for the catching-bar consisting of an outer casing, c, and a perforated plate, c', arranged 35 between the casing and the frame-section d, the perforation in said plate lying over a corresponding perforation, d', in the said frame-section, and through both of said perforations the catching-plate extends, as shown in Figs. 40 4 and 5. The casing c and plate c' may be secured to the frame-section in any suitable manner. Between the shoulder a'' and the plate c' is arranged a spiral spring, a'', which forces the catching-bar upward when released 45 by the detaining-plate b, as indicated in Figs. 3 and 5, a pin, a'', limiting the upward movement thereof.

The casing e, in which the detaining-plate is arranged, is secured to the side of the frame-section f, the detaining-plate or the portion b' 55 thereof projecting from said frame-section toward the opposite section, d, and directly beneath the end of the catching-bar, as indicated in Figs. 4 and 5. To permit this projection of the portion b' the frame-section f is cut away 60 at f', and through the opening thus made the said portion of the detaining-plate extends, as shown. The normal position of the detaining-plate is illustrated in Figs. 4 and 6, being such that as the catching-bar is depressed the 65 barbed end thereof does not pass through the opening b'', but strikes the edge b''' thereof, and as the bar continues to descend, the inclined sides of the barbed end force the detaining-plate toward the section d of the frame until 70 the barbed end passes through the opening b'', upon which the said detaining-plate springs back into the recess a'', as indicated in Figs. 4 and 5, and thus prevents the upward movement of the locking-bar. To release the said bar, 75 the plate b is pressed toward the opposite frame-section, d, by the finger-piece b', which projects out through the casing e until the opening b'' in said plate b will permit the end of the catching-bar to lift therefrom, as in Figs. 80 3 and 6. The detaining-plate is secured to the casing e at the end of the spring portion b'', as illustrated in Figs. 6 and 7.

If desirable, the plate c' may be dispensed with and the spring a'' rest directly upon the 85 top of the frame-section d; also, instead of recessing the catching-bar at a'', the bar throughout its entire length may be reduced in diameter to the thickness thereof at said recess.

Having thus described our invention, what 90 we claim is—

1. In a bag-catch, the combination of a spring-actuated catching-bar provided with an inclined or barb-shaped catching-end, a casing in which said catching-bar is arranged, 95 secured to the frame-section d, said frame-section d, a perforated yielding catching-plate, b, projecting from the frame-section f underneath the barbed end of said catching-bar, said frame-section f, and a casing in which said 100 yielding plate is arranged, attached to said frame-section f, for the purposes set forth.

2. In a bag-catch, the combination of the perforated frame-section d, a casing secured to

said frame-section, a spring-actuated catching-bar provided with a finger-piece, and a barbed catching-end arranged in said casing and moving through the perforation in said frame-section *d*, the perforated frame-section *f*, an automatically-yielding catching-plate projecting through the perforation in said frame-section *f* underneath the barbed end of the catching-bar and provided with an opening, *b*², 5 therein, and a finger-piece and a casing attached to said frame-section *f*, and to which said catching-plate is secured, for the purposes set forth.

3. In a bag-catch, the combination of the 15 perforated frame-section *d*, a casing secured to said frame-section, a catching-bar, *a*, having a finger-piece, *a'*, a barbed end, *a*³, recess *a'*, a shoulder, *a*², and pin *a*⁷, arranged in said cas-

ing and moving through the perforation in the frame-section *d*, a spiral spring arranged 20 around said bar, the perforated frame-section *f*, an automatically-yielding catching-plate, *b*, having the projecting portion *b'*, with an opening, *b*², therein, spring portion *b*⁵, and a finger-piece, *b*⁴, projecting through the perforation 25 in the frame-section *f* underneath the barbed end of the catching-bar, and a casing, *e*, for the purposes set forth.

In testimony that we claim the invention set forth above we have hereunto set our hands 30 this 12th day of January, 1887.

CHAS. REINISCH.
LOUIS OCHSE.
